UNITED STATES PATENT OFFICE.

LUDWIG HIRT, OF GREVENBROICH, GERMANY, ASSIGNOR TO THE
MASCHINENFABRIK GREVENBROICH, OF SAME PLACE.

CRYSTALLIZING APPARATUS.

SPECIFICATION forming part of Letters Patent No. 625,031, dated May 16, 1899.

Application filed June 16, 1898. Serial No. 683,596. (No model.)

To all whom it may concern:

Be it known that I, LUDWIG HIRT, a subject of the Emperor of Austria-Hungary, residing at Grevenbroich, Kingdom of Prussia, Germany, have invented a new and useful Improvement in Crystallizing Apparatus, of which the following is a specification.

My invention relates to apparatus for crystallizing the substance capable of being crystallized contained in the masse-cuite of the sugar-making process and in other solutions. Among such several purposes it is especially designed to work the process of crystallization of saccharine or other solutions, as set forth in the United States Patent to Ludwig Wulff, No. 528,497, dated October 30, 1894.

By my invention the stirrers are preferably of such construction that while they act in the two halves of the cylindrical vessel in opposite directions they thoroughly mix the masse-cuite under treatment and keep it in constant motion while crystallization is going on. They will prevent any crystallized matter from settling on the side walls or heads of said vessel. Furthermore, the stirrers may be easily separately removed from the axle and replaced by others, as will readily be seen by the following description. The device for admitting heating or cooling medium into the space of the double casing very much simplifies the connection of such parts with the outer shell of said vessel.

In the accompanying drawings I have shown one form of apparatus embodying my invention.

Figure 1 is a longitudinal section through the crystallizing vessel. Fig. 2 is a transverse sectional view of the apparatus, taken on the line $\alpha\alpha$ of Fig. 1. Fig. 3 is a detail end view 40 of the valve mechanism.

The apparatus shown in the drawings consists mainly of a cylindrical horizontal vessel A, closed at both ends by the heads X X'. The cylindrical vessel is provided with a jacket B for allowing heating or cooling medium to circulate around the vessel. This medium may be employed either in a gaseous or liquid state. For allowing the said medium to enter into the jacket a device C is arranged at one end of the jacket and at the lower side thereof. This device consists of

a L-shaped pipe a, Fig. 3, at each end of which a valve b' and b'' is arranged for admitting either the heating means or the cooling means. The outlet D at the opposite and 55 upper end of the jacket allows the heating or cooling medium to escape. An aperture E at the upper side of the jacket is arranged for introducing the masse-cuite or other solution to be treated in the vessel, and another 60 aperture F is arranged for inspecting the vessel inside, serving as a manhole and also for introducing crystals, if this becomes necessary for the process in hand. Both apertures E and F may be closed tightly by covers, and 65 they are separated from the hollow space of the jacket by suitable means. At the lower side of the jacket an outlet G, provided with a slide or valve, is arranged for permitting 70 the crystallized mass to be evacuated from the vessel. The cover c of this outlet is arranged so as to close the vessel and prevent settlement of crystallized matter in the space below the wall of the vessel A.

The vessel A is shown as provided with 75 stirrers of peculiar construction. The shaft H of these stirrers passes through the heads X X' by means of stuffing-boxes S S' and is rotated by means of a worm-wheel J and a worm K, on the shaft of which latter the pulley R is 80 fixed. The worm K may be partly situated within a trough e, so as to be lubricated by a lubricant within said trough in order to reduce the friction as much as possible.

Within the crystallization vessel the shaft 85 H is preferably of a square cross-section, and on this square part the stirring device is mounted. The stirring-blades $f' f'' f''' f'''' f'''' f''''$ f'''' are fixed on the shaft H and carry at their ends a flat iron bar g, bent into a helicoidal 90 line reaching nearly to the inner wall of the crystallizing vessel in order to avoid any settling of crystallizing mass. In order to thoroughly stir the mass, a second flat iron bar g' of a helicoidal shape is arranged in the middle of the stirring-blades, or several of such helicoidal bars g', at proper distances from each other, may be fixed to the blades. The blades $f' f'' f'''$, &c., are bent in their lengthwise direction according to the helicoidal 95 form of these flat iron bars g'.

In order that no crystals may settle on the

heads of the vessel, scrapers $h'h^2$ are arranged at the opposite ends of the stirrers, which scrapers remove all deposits on the heads of the vessel.

5 In order that the stirrer device within the vessel may be very rigid, stays i may be arranged at proper places.

The fixing of the blades on the shaft is effected by bending the blades at their innermost ends into saddles m , preferably of a $\square$ -shaped form, as shown in Fig. 2. These saddles are set onto the square shaft and conform in shape thereto and are held in this position by counter-plates n and screws $o o$.

15 Beyond this fixture the blades f are bent according to the helicoidal line of the flat bars g , to which the blades are fixed by means of screws or rivets. The helicoidal form of the flat bars and the position of the blades corresponding to that form may be of a more or less rising gradient, according to the character or condition of the masse-cuite. The gradient shown in the drawings is about fifty-three degrees on each side. The stirrers in

25 the two halves of the apparatus are placed in alternate position of one hundred and eighty degrees and are so placed that the mass on the left hand is removed toward the right and that on the right hand toward the left.

30 Having described one form or embodiment of my invention and the mode of operation thereof, I declare that what I claim, and desire to secure by Letters Patent, is—

1. A crystallizing apparatus consisting of a vessel, a surrounding jacket, a device for ad-

mitting cooling or heating means into said jacket, a manhole in the jacket and vessel, a central shaft of rectangular cross-section, blades provided with saddles m embracing and conforming to the shape of the shaft, 40 counter-plates and screws for fixing said blades to the shaft and helicoidal-shaped flat iron bars, to which said blades are fixed.

2. In an apparatus for crystallizing purposes, the combination of a central shaft of 45 rectangular cross-section, blades provided with saddles m embracing and conforming to the shape of the shaft, counter-plates and screws coöperating with the saddles to fix each blade separately to the shaft and a flat iron 50 bar bent into a helicoidal line not exceeding one-half of the inner circumference of the surrounding vessel and connected to the blades.

3. In an apparatus for crystallizing purposes the combination of a central rectangular shaft, blades provided with saddles m on their ends embracing the shaft, counter-plates, and screws to secure the saddles and blades in place on the said shaft, helicoidal flat bars fixed to the said blades and stays 60 for rigidly connecting the blades with the said shaft.

In testimony that I claim the foregoing as my invention I have signed my name, in presence of two witnesses, this 23d day of May, 65 1898.

LUDWIG HIRT.
